EXTRUSION PRESS

Paul H. Taylor, Grand Island, N.Y., assignor to Tayco Developments, Inc., North Tonawanda, N.Y., a corporation of New York

Filed Oct. 13, 1961, Ser. No. 144,955

9 Claims. (Cl. 18—5)

This invention relates to presses and more particularly to presses for forming or compressing materials which utilize liquid compressibility as a motivating force in the energy source for the press ram.

Heretofore, such presses have been of five categories:

First, there are the hydraulic presses which are characterized by low velocity but in which the velocity can be accurately modulated.

Second, there are the mechanical presses which are motivated by a crank throw or variations thereof and which, in general, generate a sine wave movement with high initial velocity, and high force with low velocity at the end of the stroke.

Third, there is the drop hammer type of press motivated by a falling weight which may or may not be accelerated by means of air or steam to accomplish the desired impact.

Fourth, there is a class of hydraulic presses in which higher velocities are obtained through the medium of stored energy accumulators in which the compression of a gaseous head provides the stored energy.

Fifth, in recent years presses motivated by explosives have been evolved.

Each of the above presses has its distinct limitations and for a particular manufacturing operation usually only one is suitable so that when there are a range of manufacturing processes, a multiplicity of presses of different types must be utilized.

The primary object of the present invention is to provide a single press which can operate with the high velocity of explosives, the accurate controllability of liquids, and the elasticity of air.

Another important object of the invention is to provide a press in which the force curve can be exactly tailored to requirements.

Another object of the invention is to provide a press having shock absorption capabilities which automatically come into operation in the event of failure of the system to work properly or in the event the operator fails to put work in the press.

Another object is to provide a simple and effective means for hydraulically loading die members against outward deflection while at the same time permitting of quick die removal. Such hydraulic loading can be controlled either hydraulically or electrically.

Another object is to provide controlled metering of the fluid to produce precise velocities while still providing rapid acceleration for the ram.

Another object is to provide such a press in which premature operation of the press is avoided, it being necessary to release a latching means or to cock the press before it can be operated.

Another object is to provide simple and rapid means for hydraulically closing the press, that is, bringing the punch up to the workpiece preparatory to the working stroke.

Another object is to provide such a press in which the working pressure can be built up in a series of pulses to a high value, a liquid having a high degree of compressibility being utilized for this purpose and the liquid being compressed by degrees to obtain the required high working force.

Another object is to provide such a press in which the workpiece can be held under compression for a long period of time, such as for a week, in the production of

2

man-made gems, and in which the degree of such compression can be held constant thermally.

Another object is to provide such a press in which the main ram is of reduced mass to cut down the flywheel effect thereof, the ram being desirably made of aluminum or titanium for this purpose. Another aim is to provide such a press which can be activated by a medium having both a high initial and also a sustained thrust, such medium being normally in the form of a gas but being used in the liquid state.

Other objects and advantages of the invention will be apparent from the following description and drawings in which:

FIG. 1 is a side elevation of a horizontal press embodying the present invention and illustrating the position of the die member for quick removal and replacement.

FIG. 2 is a fragmentary end elevational view, viewed from line 2—2, FIG. 1.

FIG. 3 is a fragmentary, horizontal, longitudinal section taken generally on line 3—3, FIG. 1, and showing on an enlarged scale, the construction of the corresponding end of the press.

FIG. 4 is an enlarged, vertical, longitudinal section through the opposite end of the press from that viewed in FIG. 3.

FIG. 5 is an enlarged, vertical, longitudinal section through an intensifier forming a source of high pressure liquid for the press.

FIG. 6 is a diagram of the hydraulic circuit.

The invention is illustrated as being in the form of a horizontal extrusion press having a horizontal body cylinder 8 mounted on a base or bed 9. The body cylinder is shown as having a working or extrusion chamber 10 having a top opening 11 through which the workpiece to be formed (not shown) is inserted in the press, and also having a bottom opening 12 through which the extrusion or forging is removed from the press and dropped into a tote pan 13 or the like. The die 14 is shown as being of frusto-conical form and as having a die cavity 15 which receives a punch 16 carried by the main ram indicated generally at 17. To reduce the mass of this ram and hence cut down its flywheel effect it can be made of aluminum or titanium.

The die 14 is contained in the correspondingly tapered bore 18 in a cylindrical die holder 19, this die holder in turn being fitted in a cylindrical end bore 20 in the smaller cylindrical end 21 of a die block indicated generally at 22. The opposite enlarged end 23 of the die block 22 is mounted in the open end of the bore 24 of the main body cylinder 8 of the press by means of an interrupted thread joint so that the die block 22, together with the die 14, can be quickly removed from the press. For this purpose, the threads 25 of the enlarged end 23 of the die block 22 are in the form of three segmental groups of threads each of 60° extent and separated by unthreaded portions 26 also of 60° extent and the mating segmental groups of threads 28 in the bore of the main body cylinder 8 are also of 60° extent and are similarly interrupted by segmental unthreaded portions 29 also of 60° extent.

With the segmental groups of threads 25, 28 interengaged, the die 14 is adequately supported in the main body cylinder 8 of the press against the axial thrust of the punch 16 against the workpiece in the die cavity 15. Upon turning the die block 22 60° so that its threads 25 are disengaged from the threads 28 and its unthreaded portions 26 is registered with the threads 28, the die block can be pulled axially out of the main body cylinder 8 to the dotted line position shown in FIG. 1. In this movement the die block 22 is shown as supported by rails 30 carried by a bed 31, these rails engaging the horizontal downwardly facing ends of the upper two groups of segmental threads 25, as best shown

in FIG. 2, to slidably support the latter. The die block 22 is shown as turned by means of a handle 32, although it will be understood that the die block could be power actuated. The bed 31 can be used to contain tools and for this purpose is shown as having doors 33 providing access to its interior. The extrusion can be ejected from the die cavity 15 by means of an ejector pin 34 which can be actuated in any suitable manner.

Liquid for actuating the press is supplied by a low pressure hydraulic pump 35 capable of primary pressures to, say, 10,000 p.s.i.g. indicated by a dial 36. This pump 35 can be supplied with liquid from a tank or reservoir 38 and its outlet line 39 connects with a two position valve 40 which is also connected by a drain or return line 41 to tank 38. Lines 42 and 43 also connect this two position valve to an intensifier indicated generally at 44 and shown in enlarged section in FIG. 5. In one position of the two position valve 40 a port 45 connects the pump outlet line 39 with the line 43 leading to the intensifier while the line 42 from the intensifier is connected by a port 46 with the drain line 41 back to tank. In the other position of the two position valve 40 it reverses the relation of these pipes, having a port 48 connecting the pump outlet line 39 with the pipe 42 and having a port 49 connecting the pipe 43 with the drain line 41.

The intensifier comprises a body cylinder 50 having a stepped blind bore 51 the large diameter portion 52 of which forms the outer open end of the bore and the small diameter portion 53 of which forms the inner blind end of the stepped blind bore. This bore contains a hollow piston or ram, indicated generally at 54, having a large diameter end 55 fitting the outer large diameter portion 52 of the stepped blind bore 51 and having an opposite small diameter end 56 fitting the inner small diameter portion 53 of the stepped blind bore 51.

An annular internal dust seal ring 58 in the bore of the body cylinder 50 is interposed between the large end 55 of the ram or piston 54 and the large diameter end 52 of the stepped blind bore 51 in body cylinder 50, this dust seal ring protecting against dust and other foreign matter an external liquid seal ring 59 on the small diameter end 56 of the ram or piston 54 and sealing against the small diameter portion 53 of the stepped blind bore 51. The ram or piston is provided with a central through bore 60, the outer end of which is enlarged to provide a cylindrical bore 61 enclosed by an end head or cap 62 screwed on the outer large end 55 of the ram with an external liquid seal ring 63 at the end of the ram interposed between the cap and the ram.

A piston 65, having an external peripheral annular liquid seal ring 66, is fitted and works in the enlarged cylindrical end 61 of the through bore 60 and is fast to a tubular stud 68 which extends coaxially through the inner smaller end 69 of the through bore 60 and is fixed to the cylinder 44 at the blind end of its stepped bore 51 by a threaded connection 70, a liquid seal 71 being provided at the base of the stud. This tubular stud has a through bore 72 which provides communication between the lines 43 and the cylindrical chamber 73 between the piston 65 and the end cap 62 of the ram 54. This chamber 73 is the low pressure inlet chamber of the intensifier. The open reduced end 69 of the bore 60 surrounds the stud 68 with substantial clearance therebetween and provides communication between the cylindrical chamber 74 on the opposite side of this piston 65 and the cylindrical chamber 76 in the small diameter portion 53 of the stepped blind bore 51. This chamber 76 is the high pressure outlet chamber of the intensifier. This high pressure outlet cylindrical chamber 76 communicates, via a passage 78 containing a check valve 79 opening away from the chamber 76, with the pipe line 42.

The cylindrical chamber 80 in the enlarged portion 52 of the stepped blind bore 51 and closed by the piston 54 contains air and is protected by the dust seal ring 58.

The cylindrical high pressure outlet chamber 76 communicates, via a passage 81 containing a check valve 82 opening away from the chamber 76, with a pipe line 83 connecting the intensifier with the press. The pressure in this line 83 can be indicated by a high pressure gage 84, this gage indicating the working pressure of the liquid which is compressed to actuate the press.

A line 85, containing a valve 86, also connects with the passage 81 on the side of the check valve 82 remote from the high pressure outlet chamber 76 of the intensifier, this line leading back to the tank 38 as shown in FIG. 6. This valve 86 can be opened automatically or manually and serves to return the spent compressible actuating liquid from the press to the tank 38 for reuse.

An important feature is that the diameter of the enlarged cylindrical outer end 61 of the through bore 60 is greater than the diameter of the inner stepped blind end 53 of the blind bore 51, this differential determining the effective size of the ram 54 in producing intensified pressure in the line 83 in response to the pump pressure applied from the line 43. This pressure is transmitted through the bore 72 in the stud 68 to the cylindrical low pressure inlet chamber 73 between the piston 65 on this stud and the end cap 62 of the ram. In this intensifier the applied force is increased in intensity by reason of the stepped ram 54 interposed between the piston 65 and stepped cylinder 50. Thus delivery from the pump 35 through the line 43 passes through the bore 72 of stud 68 into the cylindrical low pressure inlet chamber 73 of the stepped ram 54 and drives this ram outwardly or to the left as viewed in FIG. 5. This causes the piston 65 to reduce the size of the cylindrical chamber 74 and hence force liquid from this cylindrical chamber through the bore 69, cylindrical high pressure outlet chamber 76, check valve 82 and passage 81 to the line 83 leading to the extrusion press. At the same time the smaller end 56 of the ram 54 is withdrawing from the cylindrical high pressure chamber 76 and hence subtracting from the liquid so delivered into this cylindrical, high pressure outlet chamber by the piston 65. Accordingly the volume of liquid delivered to the line 83 will be proportional to the differential in cross sectional area of the cylindrical chambers 74 and 76 and at a corresponding intensified pressure. Liquid at such intensified pressure, and indicated on the gage 84, is preferably so fed to the extrusion press through the line 83 in a series of pulses and return of the stepped ram 54 is effected by moving the two position valve 40 so as to connect its ports 48 and 49 with the lines 42 and 43, respectively. In this position the delivery from the pump 35 is to the line 42 past check valve 79 into the cylindrical high pressure outlet chamber 76 and through the bore 69 into the cylindrical chamber 74. Since the cross sectional size of the cylindrical chamber 74 is greater than the cross sectional size of the cylindrical high pressure outlet chamber 76 the stepped ram 54 will be moved inwardly or to the right as viewed in FIG. 5 and the liquid displaced from the cylindrical low pressure inlet chamber 73 by this movement of the stepped ram escapes through the bore 72 of the stud 68, line 43 and port 49 of the two position valve 40 to tank 38.

While any compressible liquid can be used as the actuating fluid, the use of a normally gaseous fluid, such as butane, propane or nitrous oxide in liquid form during initial movement of the ram is contemplated to obtain the initial thrust energy of high value from the fluid as a compressed liquid and thereafter to obtain sustained thrust from the fluid as a compressed gas.

Referring to FIGS. 3 and 4, the main ram 17 is in the form of a tubular body 90 having its end carrying the punch 16 closed by an end head 91 screwed therein, an external annular liquid seal ring 92 being provided on the end head 91 and the punch 16 being removably secured to the end head 91 by means of a suitable holder 93. A circular gasket ring 94 within the main ram 17 is carried by an axially projecting marginal portion of the end

head 91. The tubular body 90 is provided at the end enclosed by the end head 91 with an enlarged piston head 95 working in the bore 24, an external annular seal ring 96 being provided on this piston head between it and the bore 24 and the piston head 95 providing a space or chamber 98 extending along the tubular body 90. At the opposite end of this tubular body the bore 24 is enlarged, as indicated at 99 and the tubular body is provided with a piston head 100, containing an external annular liquid seal ring 101 working against this enlarged cylindrical section 99 of the bore 24. In this enlarged cylindrical section 99 of the bore 24 is also slidably fitted a cylindrical follower 102 which can be moved to close the press and also to bring the punch 16 to a proper distance from the billet to insure impact at the optimum velocity for the particular work involved. This follower has an external annular liquid seal ring 103 working against the bore section 99 and is provided with a cylindrical blind bore 104 at the end opposing the main ram 17. In this cylindrical bore 104 is slidably fitted a reduced cylindrical end 105 of the cylindrical body 90 of the main ram 17, this reduced cylindrical end having an external annular liquid seal ring 106 in contact with this bore. The follower 102 is backed by a threaded end head 108 screwed into the corresponding end of the main body cylinder 8 and having an external annular liquid seal ring 109 in contact with the enlarged section 99 of the bore 24.

A control liquid line 110 in the end head 108 communicates with the prefill space 111 between this end head 108 and the follower 102, this permitting of hydraulically adjusting the position of the follower 102 so as to close the press, that is, to bring the punch 16 into contact with the billet in the die cavity 15 preparatory to the working stroke of the press if this type of use is desired. This adjusting the position of the follower 102 also permits of bringing the punch to the correct distance from the billet in the cavity 15 to insure that the punch 16 strikes the billet at the optimum velocity for the work involved. A control liquid line 112, shown as under control of a solenoid valve 107, communicates with the space 113 between the follower 102 and the piston head 100, this line being used to initiate or trigger the working stroke of the press. A control liquid line 114 communicates with the space 98 surrounding the main ram 17 between its piston heads 95 and 100, this line being used to cock or prevent premature operation of the press. The area 115 of the piston head 100 which forms an end wall for the chamber 98 is effective for this purpose.

A stud 116 is connected by a screw joint 117 with the follower 102, this joint having an annular oil seal ring 118. This stud projects into the cylindrical bore 119 of the tubular body 90 of the main ram 17 through a coaxial bore 120 through the end head of the reduced cylindrical end 105 of the main ram 17, the stud 116 being slidably fitted in this bore 120. Such sliding fit, as compared with the microfit of the sliding surfaces of the body cylinder 8, main ram 17 and piston 65, provides a clearance exaggerated in FIG. 4, which permits the passage of liquid under the very high pressures used in the press. The tolerance at this point provides a frictional resistance to the passage of liquid during the pressing stroke of the press. At its opposite end the stud 116 has a piston head 121 working in the bore 119 and seating against the gasket ring 94. This piston head 121 is provided with an external annular peripheral liquid seal ring 122 and an important feature of the invention is the provision of holes or passages 123 through the piston head 121 and terminating against the gasket ring 94. The space bounded by the main ram end head 91, gasket 94 and piston head 121 is indicated at 124.

A feature of the invention resides in the provision of an enlargement or spool 125 in an intermediate part of the stud 116, the clearance between the periphery of this spool and the bore 119 of the tubular body 90 being limited so as to provide frictional resistance to the passage

of liquid thereby during the pressing stroke of the press. The threaded end of the stud 116 is provided with an axial blind bore 126 having ports 127, 128 communicating respectively, with the interior 119 of the main ram 17 and the cylindrical bore 104 in the follower 102. This blind bore forms a continuation of an axial bore 130 in an integral axial stem 131 projecting from the follower 102 and slidably fitted in a bore 132 in an axial extension 133 of the end head 108, annular internal liquid seal rings 134, 135 being provided around the stem 131. The bore 130 communicates with the line 83 connecting the press with the intensifier 44 this line having for this purpose a fitting 136 screwing into an internally sealed ring 137 fitted around the extension 133 and communicating with the bore 130 through ports 138 and 139 provided respectively in the sides of the extension 133 and the stem 131.

The speed of press operation is adjustably controlled by a restriction valve stem 140 arranged coaxially in the bores 126 and 130 and having a tapered end head 141 between the ports 127 and 128. A feature of the invention resides in the closeness of fit of this restriction valve stem 140 in the bore 126, this fit being such as to provide a high degree of frictional resistance to the rapid passage of liquid through this bore between the ports 127 and 128. The opposite threaded end 142 is screwed into the outer threaded end of the bore 130 and projects to the exterior of the press for adjustment, being shown as provided with a screw driver slot 143 for this purpose. An annular internal liquid seal ring 144 is provided in the bore 130 around the restriction valve stem 131.

30 A feature of the invention resides in the ready removability of the die 14 and die holder 19 from the die block 22 while at the same time holding the die against extremely high stress pressures of the expansion force of the billet being extruded. The normal practice with extrusion dies is to apply a succession of conical shrink rings to the die holder to increase the resistance to deflection of the contained die so that the die will not fail in service. Such shrink rings must be large and render removal of the die and die holder from the press difficult and costly.

40 Considering the die holder 19, and die blocks 22 as a heavy walled vessel, it is well known that with a heavy walled vessel the stress levels in the wall rapidly diminish as the distance from the axis of the vessel. Thus if at the core of the die 14 the stress level is, say, 200,000 p.s.i.g., to withstand extrusion pressures of 100,000 p.s.i.g., the stress level at the exterior of the die would be in the order of 100,000 p.s.i.g., the stress level at the exterior of the die holder 19 would be in the order of 50,000 p.s.i.g., and the stress level at the exterior of the die block 50 22 would be in the order of 20,000 p.s.i.g.

55 In accordance with the present invention liquid under such assumed pressure of 20,000 p.s.i.g. is applied to the exterior of the die block 22 around the die holder and die to provide resistance to the outward yield or deflection of the die, while at the same time providing normal sliding clearances between the die, die holder and block when pressure is relieved so that they can be readily separated.

60 Preferably the structure for accomplishing this also expands into engagement with the bore of the horizontal body cylinder 8 so that the body cylinder also resists the outward yield or deflection of the die and liquid under pressure is also shown as applied to the exterior of the body cylinder 8 around the die further to relieve such 65 expansion stress against the body cylinder and permit of using a less bulky body cylinder.

To this end an annular pressure ring 145 is shown as having its bore fitted, with normal sliding clearance, around the periphery of the cylindrical end 21 of the die block 22 and as having this bore provided with a broad central annular channel 146 and this bore also provided with internal liquid seal rings 148 on opposite sides of this channel. The periphery of this pressure ring 145 is similarly fitted, with normal sliding clearance, in the bore 70 24 of the horizontal body cylinder 8 and external liquid

seal rings 149 are provided in this periphery near its opposite ends. Liquid under pressure is supplied through registering ports 150 and 151 through the pressure ring 145 and body cylinder 8, respectively, and liquid under pressure can be supplied to these ports by a pressure ring 152 fitted to the exterior of the main body cylinder 8 and having a broad central annular channel 153 in its bore which is in register with the port 151 and is supplied with fluid under pressure from a supply line 154. Internal liquid seal rings 155 around the ends of the bore of this pressure ring 152 prevent leakage of this liquid from between this pressure ring and the periphery of the horizontal body cylinder 8. In place of or in addition to the pressure of the liquid supplied from the line 154, one or more electric resistance immersion heaters 156 can be contained in the liquid in the channel 153 to heat and expand the body of liquid therein and thereby elevate its pressure to the value required to resist outward yield of the die 14 and the parts surrounding the die. The pressure of the liquid in this system can be indicated by a gage 158.

Pressure can be further intensified or held constant behind the main ram 17 of the extrusion press by heat, this being shown as accomplished by circulating a high temperature liquid in the annular space 98 surrounding the press ram, this being for the purpose of getting higher peak performance out of a press of a given pump capacity or to obtain constant operating pressures for a long period of time such as in producing man made gems, such as diamonds, sapphires and the like, which are grown under high pressure for periods of as long as a week. With the press of the present invention maintenance of a constant high pressure on the gems could quite easily be accomplished by thermal means rather than the pulsation of the press system through the intensifier 44 and low pressure pump 35.

For this purpose, liquid of the desired temperature can be recirculated through a branch line 160 of the liquid control line 114 leading to one end of the space 98 around the main ram and a line 161 connecting with the other end of this space. These lines 160, 161 are shown as connecting with a heat exchanger 162 the heating medium for which can be heated in a heater 163. If required the working liquid behind the main ram could be cooled before being introduced to the press and also a coolant could be supplied to the heat exchanger 162 during the period of mechanical build up by pulses of the working pressure behind the main ram by the intensifier 44.

Operation

The principal feature of the press of the present invention resides in the utilization of liquid compressibility as the motivating force in the energy source for the press room to obtain the required working pressures and explosive action of the press if required. To this end it is desirable to use a liquid having a relatively high degree of compressibility.

Such liquid can be a silicone having a high degree of compressibility, but the use of a liquid-gas, that is, a fluid normally gaseous but compressed into a liquid is especially contemplated. Examples of such gases are butane, propane and nitrous oxide. Considering liquid propane, for example, this gas in liquid form has a substantially greater degree of compressibility than liquid silicone of the highest compressibility known to provide a greater movement of the ram 17 as a function of the compression of the liquid. In addition, by conversion to its gaseous phase on continued movement of the ram, a sustained thrust is maintained which could not be obtained from mere decompression of a liquid. Thus such liquid gases have the energy storage characteristics of low pressure gases multiplied by high pressures when in liquid phase to store as much as twice the energy for a given volume as compared with pure liquids but behaving, by transition to their gaseous phase, as gases in providing

reduced resistance to passage through small orifices and behaving as liquids in storing the energy required to compress the liquid. Such liquid-gases can be controlled with great accuracy through smaller orifices than will pass equivalent amount of pure liquids due to transition to the gas phase on release from the orifices. This function provides liquid flow control through smaller orifices which can be of importance in achieving compactness of design.

Such liquid having a high degree of compressibility is contained in the tank 38 or as a liquid gas in a pressurized tank and is withdrawn therefrom and delivered at low pressure, say at 10,000 p.s.i.g. to the intensifier 44 and thence behind the ram 17 of the press.

In preparation for the cold extrusion operation, a die 14 must be installed in the press and to this end the die block 22 is rotated in its interrupted thread joint 60° or a sixth of a revolution so as to disengage its thread segments 25 from the thread segments 28 in the end of the body cylinder 8 and bring the thread segments 28 into line with the unthreaded portions 26 of the die block 22 so that the die block can be withdrawn axially from the bore 24 in the horizontal body cylinder 8. In being so withdrawn, the downwardly facing ends of the two top groups of thread segments 25 on the die block 22 lie in a common horizontal plane intersecting the major axis of the press, as best shown in FIG. 2, and these downwardly facing ends ride on the side rails 30 of the press frame so as to support the die blocks while it is being taken from and inserted in the press.

After being withdrawn, as shown by dotted lines in FIG. 1, a cylindrical die holder 19 is inserted in the bore 20 of the die block 22 and a tapered die 14 is inserted in the conical bore 18 in this die holder, normal sliding clearances being provided between these parts so that they can be readily assembled. The die block 22 is then slid back into its operative position within the horizontal body cylinder 8, the horizontal bottom ends of its two upper groups of thread segments 25 riding on the rails 30 during such insertion so as to support the die block and guide it in its movement to operative position. When the die block 22 has been fully inserted it is given a 60° turn, as by means of its handle 32, to re-engage its thread segments 25 with the thread segments 28 of the horizontal body cylinder 8 and to latch these two parts together in operative relation.

Fluid of any suitable character under suitable pressure, say 10,000 p.s.i.g., is then applied to the line 154 into the pressure ring 152 surrounding the horizontal body cylinder 8 and this fluid pressure is transmitted through the ports 151 and 150 into the internal channel 146 of the pressure ring 145 interposed between the periphery of the cylindrical part 21 of the die block 22 and the bore 24 of the horizontal body cylinder 8. Leakage of this fluid beyond the opposite ends of these pressure rings is prevented by the pairs of annular liquid seal rings 148, 149 and 155 and the pressure in the broad internal annular channels 146 and 153 thereby resist outward yield or deflection of the die 14, die holder 19, die block 22 and main body cylinder 8 under the extrusion pressures subsequently applied.

The billet (not shown) is then inserted into the die cavity 15 and the press closed to bring the punch into proper spatial relation to this inserted billet. This adjustment of the starting position of the punch can be such that the punch is spaced from the billet a distance to acquire an optimum velocity for forming the billet, this capability being a feature of the invention. This adjustment also adjusts the travel of the punch in forming the billet into the extrusion.

To accomplish this, fluid of any suitable character is introduced under pressure through the line 110 into the space 111 between its end head 108 and the cylindrical follower 102 to the left as viewed in FIG. 4 thereby to move the main ram 17 along the bore 24 so as to bring its punch 16 toward the die cavity 15 and into the optimum

spatial relation with the billet (not shown) therein. When this is done, the liquid so admitted through the line 110 is held trapped within the space 111 between the follower 102 and main body cylinder end head 103 to serve as a backing for the follower against the subsequently applied extrusion pressures. It is unnecessary, therefore, that the liquid so admitted through the line 110 be of a compressible character.

The speed of forming the extrusion is then adjusted by turning the restriction valve stem 140 as by its exposed screw driver slot 143, FIG. 4.

The first phase of the pressing operation is to establish a seal at the gasket 94 between the main ram 17 and the piston 121 at the end of the stud 116. For this purpose liquid of any suitable character is introduced under pressure through the line 114 into the space 98 and is thereby impressed against the face 115 of the piston head 100. This moves the main ram 17 to the right as viewed in FIGS. 3 and 4 and thereby compresses the gasket 94 between the end head 91 of the main ram 17 and the piston head 121 of the stud 116, thereby to establish a seal around the ends of the passages 123 of the latter. At this time the valve 86 is open to permit the escape of liquid from behind the main ram. While this seal is subsequently additionally maintained by the working pressure introduced into the main ram bore 119 behind the stud piston head 121, during the build up of this working pressure, the pressure in the chamber 98 is preferably maintained at a high enough valve to insure the maintenance of the seal at the gasket 94 to provide against premature operation of the press. As long as the effective area of the face 115 of the piston head 100, in relation to the liquid pressure in the chamber 98, is greater than the effective total area of the bores 123 in the stud piston head 121 against the gasket 94, in relation to the working pressure in the bore 119 of the main ram, the main ram is held sealed, via the gasket 94, against the stud piston head 121. The areas and pressures involved can be readily calculated to achieve this.

The next phase of the pressing operation involves closing the valve 86 and introducing, in pulses, a compressible liquid into the bore or chamber 119 in the main ram 17 to build its pressure up to the working levels in which the liquid in this bore or chamber is compressed to a high degree to have a high degree of stored explosive-like energy. As this pressure is built up to working values in pulses, this increasing pressure also serves to maintain the seal of the gasket 94 against the stud piston head 121 so that even in the event of failure of pressure in the chamber 98 to maintain this seal, premature operation of the press will nevertheless be prevented. In this function the increasing pressure in the bore 119 of the main ram 17 is impressed against that internal portion of the piston head 100 and its cylindrical extension 105 equal to the difference in diameter between the bore 119 of the body cylinder of the main ram and the chamber 104 in the follower 102. Since this differential area always exceeds the effective total cross sectional area of the passages 123 against the gasket 94, this rising working pressure increases the sealing value of this gasket.

The compressible actuating liquid is supplied by the pump 35 and is built up to working value and delivered in pulses to the bore 119 of the main ram 17 by the intensifier 44. For each pulse, the two position valve 40 is moved to the position shown in FIG. 6. In this position the compressible liquid is delivered by the pump 35 from the tank 38 via line 39, valve port 45, line 43 and bore 72 of stud 68 to the low pressure inlet chamber 73 between the piston head 65 at the end of this stud and the end head 62 of the ram 54. This moves this ram 54 to the left as viewed in FIG. 5 thereby to force the compressible liquid from the chamber 74 through the bore 69 of the ram into the high pressure outlet 76 of the cylinder 50 and thence past the check valve 82 through the line 83 to the press. The pressure of the compressible

liquid so leaving through the line 83 is intensified as compared with the pressure of the liquid admitted to the intensifier 44 in the low pressure inlet chamber 73 in accordance with the differential in cross sectional area of the larger bore 61 forming this low pressure inlet chamber 73 and the smaller bore 53 forming the high pressure outlet chamber 76. Obviously this differential can be designed to any value, an increase in pressure being accompanied, however, by a reduction in volume of liquid transmitted by the intensifier.

It is desirable to build up the required volume and pressure of the compressible liquid in the bore 119 of the main ram 17 of the press in a series of pulses obtained by moving the two position valve 40 back and forth between its two positions. Thus after each filling impulse as above described, this two position valve 40 can be moved to bring its ports 48, 49 into service. When this is done, the build up of working pressure in the press is maintained by the check valve 82 in the outlet 81, 83 from the intensifier 44, FIG. 5, but the pump 35, outlet line 39 is connected via port 48, high pressure outlet chamber 76 and oversize bore 69 into the chamber 74 in the ram 54. This drives the ram 54 to the right as viewed in FIG. 5, this movement again being due to the differential in cross sectional areas of the bore 61 forming the low pressure inlet chamber 73 and the bore 53 forming the high pressure outlet chamber 76, this differential area being effective as the wall surface forming the chamber 74 to move the ram to the right as viewed in FIG. 5. This compresses and purges the liquid in the low pressure inlet chamber 73 of the intensifier, this liquid flowing out through the bore 72 of the stud 68 and thence through line 43, valve port 49 and line 41 back to the tank.

The compressible liquid so supplied in pulses by the intensifier 44 via line 83 to the press flows around the stem 140 of the restriction valve in the bore 126 of the stud 116 and thence through port 127 into the chamber formed within the main ram 17 of the press by its bore 119. In this movement, while the cylindrical diameter of the stem 140 of this restriction valve is closely fitted to the bore 126 to have a high degree of frictional resistance to the high speed passage of compressed liquid from the interior of the ram 17 during the extrusion or working phase of the press, this close fit does not materially impede the feed of liquid from the intensifier in pulses to be compressed in the main ram 17 due to the fact that the build up is at a slower rate and in a succession of pulses. If objectionable resistance during buildup of pressure were encountered it is obvious that there is no necessity for introducing the feed liquid through this bore and that a separate inlet passage could be provided from the line 83 into the bore 119 of the main ram 17.

After the pressure of the compressible liquid in the bore 119 of the ram has been built up to the value necessary to compress it and reduce its volume to have the required high amount of stored energy for the extrusion operation, the press is first cocked or readied for operation by relieving the pressure maintained via line 114 in the chamber 98 and preferably also by draining or purging the liquid out of this chamber. At this time this has no effect except to release the pressure against the face 115 of the piston head 100 which pressure initially set up the seal of the gasket 94 and during the period of working pressure buildup maintained this pressure to insure against premature operation of the press.

The working stroke of the press is then initiated by energizing the solenoid valve 107 to introduce liquid under pressure through the line 112 into the chamber 113. Such introduction builds up pressure at the external end of the main ram 17 opposing the follower 102 and reverses the condition of unbalance of the ram theretofore maintained by the total area of the passages 123 against the sealing gasket 94 as opposed to the dif-

ferential internal piston area at the other end of the ram 17 represented by the difference in cross sectional area between the bores 119 and 104 of the main ram 17 and follower 102, respectively.

With such introduction of liquid under pressure into the chamber 113 the main ram 17 is immediately moved to the left as viewed in FIGS. 3 and 4 a sufficient distance to break the seal of the gasket 94 against the ends of the passages 123 through the piston head 121 of the stud 116. Accordingly the liquid in the ram bore 119 behind the stud piston head 121 and under a state of high compression with accompanying stored energy passes through the passages 123 into the chamber 124 and against the full internal area of the end head 91 of the main ram. As a result the ram can be driven with explosive force to the left as viewed in FIGS. 3 and 4 to drive the punch 16 into the billet (not shown) contained in the die cavity 15 and to extrude or forge this billet to the required shape.

With a given setting of the follower 102 and a given operating pressure the speed of movement of the main ram 17 during this working stroke of the press is controlled by a number of elements. Thus the passages 123 restrict the flow of liquid as above described. Also the spool 125 restricts the movement of liquid from the trailing end of the main ram 17 to the forward end thereof. Also liquid can escape past the surface 120 from the chamber 119 to the chamber 104 and this can be calculated to be of any desired value and provided by leaving a corresponding clearance at this surface. Also the sliding fit of the bore 120 provides a clearance in bypass relation to the adjustable restriction valve 140, this clearance being exaggerated in FIG. 4.

In addition, moreover, this speed of movement of the ram is adjustably controlled by the setting of the valve stem 140 as by its screw driver slot 143. If an explosive speed is desired, this valve stem is backed off so that its pointed end 141 is beyond the port 128 to the bore or chamber 104 in the follower 102. In this position the valve stem 140 offers practically no resistance to the flow of liquid from the bore 119 of the main ram 17 through port 127, passage 126 and port 128 into the bore 104 of the follower 102. Lacking such resistance the main ram can perform its working stroke with explosive violence.

To slow down the working stroke, the valve stem 140 is progressively advanced to first move its pointed end 141 across the port 128 and then to bring its full cylindrical cross sectional diameter into that section of the bore 126 between the ports 127 and 128. This full cross sectional diameter of the valve stem 140 has a sufficiently close fit in this bore 126 to provide a capillary action and hence a high degree of resistance to the flow of liquid at pressing speeds and this high degree of resistance can be increased by progressing the valve stem further into the bore 126 toward the port 127. The adjustment of such a valve can slow its working stroke from one of explosive action to one equalling the slowest commercial hydraulic press on the market.

After the working stroke the punch 16 can be withdrawn from the extrusion in the die cavity 15 by opening the valve 86, FIG. 6, and relieving the pressure in the chamber 140, via line 112 and solenoid valve 107 so that the liquid will exhaust therefrom and by reintroducing liquid under pressure via line 114 into the chamber 98, the piston head 100 acting as a pullback piston to withdraw the main ram 17 and its punch 16 from the extrusion. In such pullback movement of the punch, the compressible liquid in the chamber 124 between the end head 91 of the main ram 17 and the stud piston head 121 flows back through the passages 123 in this stud piston head into the bore 119 of the main ram 17 and thence through the port 127, passages 126 and 130, line 83, passage 81 in intensifier 44 and line 85 past open valve 86 back to tank 38.

The extrusion is then removed from the die cavity 15 by the action of the ejector pin 34 which forces the extrusion from the die cavity 15 into the working chamber 10 to fall by gravity through the bottom opening 12 into the tote pan 13. The press is then ready for another sequence of operations.

To remove or replace the die 14, pressure applied by the line 154 is relieved thereby to relieve pressures exerted radially inwardly against the cylindrical die holding end 21 of the die block 22 and the surrounding portion of the main horizontal body cylinder 8 by the channels in the peripheries of the pressure rings 145 and 152, respectively. This reestablishes the original normal sliding tolerances between the die 14 and die holder 20 as well as between this die holder and the die block 22, so that by turning the die block 60° to bring the segments of the thread 28 of the main horizontal body cylinder 8 into line with the unthreaded portions 26 of the die block 22, the latter can be withdrawn axially on the rails 30 to expose the die and die holder and permit them ready removal from the die block.

As previously described, instead of fluid pressure from the line 154 to so hold the die 14 against outward deflection under extrusion pressures, the liquid can be trapped in the connected channels 146 and 153 of the pressure rings 145 and 152, respectively, and then heated, through energizing the electrical resistance immersion heating units 156, to expand the fluid and supply the required compressive pressure on the die block 22 and main body cylinder 8, respectively.

Likewise liquid pressure can be intensified within the bore 119 by the recirculation of high temperature liquid in the space 98 between the main ram 17 and the surrounding main body cylinder 8. This liquid is circulated via the lines 160, 161 through the heat exchanger 162 which can be supplied with a heating medium from the heater 163. Such maintenance of constant pressure by heat could be particularly useful for a long period pressing operation, as of a week, in producing man made gems. A cooling medium can also be passed through the heat exchanger 162.

From the foregoing it will be seen that the press of the present invention is essentially motivated by the forces stored within liquids capable of compression and which can operate with the velocities of explosives, the controllability of liquids and the elasticity of air. It will further be seen that the press is capable of very heavy duty and wide variety of purposes, especially for pressing operations running into days of time. Further, the die can be quickly and easily changed even when in use it is subjected to heavy expansive pressures. Also a novel intensifier is provided for building up the necessary high pressure from a relatively low pressure source.

I claim:

1. In a press motivated by the expansive force of a compressible liquid under compression, a tubular main ram having an end head at one end and being provided with an opening at its other end, a main cylinder slidably containing said main ram and forming a closed chamber with said end of said main ram provided with said opening and said closed chamber containing said compressible liquid, means compressing said liquid in said chamber to a required working value, a head fixed to said main cylinder and arranged in said main ram against said end head and isolating said end head from said liquid in said chamber while being so compressed, and means conducting said liquid from said chamber to between said fixed head and said end head when said compressible liquid in said chamber has been compressed to said required working value.

2. In a press motivated by the expansive force of a compressible liquid under compression, a tubular main ram having an end head at one end and being provided with an opening at its other end, a main cylinder slidably containing said main ram and forming a closed

chamber with said end of said main ram provided with said opening and said closed chamber containing said compressible liquid, means compressing said liquid in said chamber and main ram to a required working value, a stud fixed with reference to said main cylinder and projecting through said opening at said other end of said main ram, a piston fixed to the outboard end of said stud and slidingly fitted in said main ram and isolating said end head of said main ram from said liquid in said chamber while being so compressed, and means conducting said liquid from said chamber to between said piston and end head when said compressible liquid in said chamber had been compressed to said required working value.

3. In a press motivated by the expansive force of a compressible liquid under compression, a tubular main ram having an end head at one end and being provided with an opening at its other end, a main cylinder slidingly containing said main ram and forming a closed chamber with said end of said main ram provided with said opening and said closed chamber containing said compressible liquid, means compressing said liquid in said chamber and main ram to a required working value, a stud fixed to said main cylinder and projecting through said opening at said other end of said ram, a piston fixed to the outboard end of said stud and slidingly fitted in said main ram and isolating said end head of said main ram from said liquid in said chamber while being so compressed, means providing a valve seat on said end head opposing said piston, said piston being provided with a passage therethrough having one end seating against and closed by said valve seat, and means moving said main ram relative to said piston to unseat said one end of said passage from said valve seat when said compressible liquid in said chamber has been compressed to said required working value.

4. In a press motivated by the expansive force of a compressible liquid under compression, a main ram having an end head, a main cylinder slidingly containing said main ram, a head fixed to said main cylinder and arranged against said end head of said main ram, said main cylinder and its fixed head forming a closed chamber on the side of said fixed head remote from said end head, means compressing said liquid in said chamber to a required working value, said fixed head isolating said end head from said liquid in said chamber while being so compressed, means providing a valve seat on said end head opposing said fixed head, said fixed head being provided with a passage therethrough having one end seating against and closed by said valve seat, and means moving said main ram relative to said fixed head to unseat said face of said one end of said passage from said valve seat when said compressible liquid in said chamber has been compressed to said required working value, comprising a piston fixed to said main ram and working in a bore formed in said main cylinder, and means arranged to introduce fluid under pressure into said bore on the side of said piston to force said end head away from said fixed head.

5. In a press motivated by the expansive force of a compressible liquid under compression, a tubular main ram having an end head at one end and being provided with an opening at its other end, said other end being of less external diameter than the end of said main ram at said end head, a main cylinder with a blind bore having a larger diameter part slidingly fitting said end of said main ram at said end head and having a smaller diameter part slidingly fitting said other end of said ram, a stud fixed to said main cylinder and projecting into the open end of said main ram, a piston fixed to the outboard end of said stud and slidingly fitted in said main ram, said piston, main ram and blind bore forming a closed chamber, means compressing said liquid in said chamber to a required working value, means providing a valve seat on said end head opposing said piston, said piston being provided with a passage therethrough having one end seating

against and closed by said valve seat, said passage terminating in a face held seated by the preponderating pressure of said compressible liquid in said chamber against said main ram, as a function of the differential in diameters between said large and small diameter parts of said bore, in the direction to hold said end head and piston together, and means moving said main ram relative to said piston to unseat said one end of said passage from said valve seat when said compressible liquid in said chamber has been compressed to said required working value.

6. In a press motivated by the expansive force of a compressible liquid under compression, a main ram having a chamber therein, a main cylinder having a blind bore slidingly containing said main ram and forming a closed chamber behind said main ram, a stem extending lengthwise of the line of movement of said main ram through both of said chambers and slidingly fitting a bore in the wall of said ram separating said chambers, a passage in said stem having a port communicating with each of said chambers and communicating with the exterior of said main cylinder, means exterior of said main cylinder supplying said compressible liquid to said passage at a pressure sufficient to compress the liquid in said chambers to the required working value, and valve means in said passage adjustable from the exterior of said main cylinder and controlling the flow of said liquid through said passage between said ports from said chamber in said ram to said chamber behind said ram, thereby to control the speed of operation of the press.

7. In a press motivated by the expansive force of a compressible liquid under compression, a main ram, a main cylinder having a blind bore slidingly containing said main ram and forming a closed chamber behind said main ram, a follower slidily fitted in said blind bore in said closed chamber and dividing said closed chamber into two separate compartments, means introducing a liquid into the compartment between the blind end of said bore and said follower to position said follower and main ram with reference to said main cylinder, means introducing and compressing to the required working value said compressible liquid into the compartment between said follower and said main ram, means holding said ram against movement while said compressible liquid is so being introduced and compressed, and means releasing said holding means when said compressible liquid has been so compressed to said required working value.

8. In a press motivated by the expansive force of a compressible liquid under compression, a main ram having a chamber therein, a main cylinder having a blind bore slidingly containing said main ram and forming a closed chamber behind said main ram, a follower slidily fitted in said blind bore in said closed chamber and dividing said closed chamber into two compartments, a stem projecting from said follower lengthwise of the line of movement of said main ram into the chamber in said main ram and slidily fitted in an opening in the wall of said main ram separating said chambers, a second stem in line with said first stem projecting from said follower to the exterior of said main cylinder and slidily fitted in an opening in said main cylinder, a bore through said stems connected by a port with said chamber in said main ram and by a second port with the compartment between said main ram and follower, means introducing a liquid into the compartment between the blind end of said first mentioned bore and said follower to position said follower and main ram with reference to said main cylinder, means introducing and compressing to the required working value said compressible liquid into said second mentioned bore to enter said chamber within said ram and said compartment between said ram and follower, means holding said ram against movement while so being introduced and compressed, and means releasing said holding means when said compressible liquid has been so compressed to said required working value.

9. In a press motivated by the expansive force of a compressible liquid under compression, a tubular main ram having an end head at one end and having an end wall provided with an axial slideway opening at its opposite end, a main cylinder slidably containing said main ram and forming a closed chamber with said end wall of said main ram, a follower slidably fitted in said blind bore in said closed chamber and dividing said closed chamber into two compartments, a stud projecting axially from said follower in closely fitted relation to said slideway opening into said main ram, a stem in line with said stud projecting from said follower to the exterior of said main cylinder and slidably fitted in an opening in said main cylinder, a bore through said stem and stud connected by a port with the interior of said main ram and by a second port with the compartment between said main ram and follower, means introducing a liquid into the compartment between the blind end of said first mentioned bore and said follower to position said follower and main ram with reference to said main cylinder, means introducing and compressing to the required working value said compressible liquid into said bore in said stem and stud to enter the interior of said main ram and said compartment between said main ram and follower, a piston in said main ram fixed to the end of said stud against said end head and substantially isolating said end head from said liquid in the interior of said main ram, means concluding said liquid from the interior of said main ram to between said piston and end head of said

10
